(57) **CLAIM**

The ornamental design for a floor lamp, as shown and described.

DESCRIPTION

FIG. 1 is a first perspective view of a floor lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the floor lamp thereof;

FIG. 10 is a perspective view of another state of the floor lamp thereof;

FIG. 11 is a perspective view of another state of the floor lamp thereof; and,

FIG. 12 is an enlarged view of the selected portion 12 in FIG. 2.

The broken lines shown in the drawings depict portions of the floor lamp that form no part of the claimed design. The dash-dot-dash broken lines show the boundaries of the enlarged views and form no part of the claim thereof.
